(57) **CLAIM**

The ornamental design for a stabilization device, as shown and described.

DESCRIPTION

FIG. 1 is a perspective view of a stabilization device according to the present design;

FIG. 2 is a right side view of the stabilization device of FIG. 1;

FIG. 3 is a left side view of the stabilization device of FIG. 1; FIG. 4 is a top view of the stabilization device of FIG. 1; FIG. 5 is a front view of the stabilization device of FIG. 1; FIG. 6 is a back view of the stabilization device of FIG. 1; and, FIG. 7 is a perspective view of the stabilization device of FIG. 1, showing an object being held in one possible orientation. The claimed design comprises the elements shown in solid lines, the elements shown in dotted lines forming no part of the claimed design.
